(57) CLAIM

The ornamental design for a ski sock, as shown and described.

DESCRIPTION

FIG. 1 is a right side elevational view of a ski sock; FIG. 2 is a left side elevational view of the ski sock from FIG. 1; FIG. 3 is a front elevational view of the ski sock from FIGS. 1-2; and,

FIG. 4 is a rear elevational view of the ski sock from FIGS. 1-3.

The broken lines are for the purposes of illustrating environment only. None of the broken lines form part of the claimed design.
